UNITED STATES PATENT OFFICE.

JOHN P. QUINN, OF NEW YORK, N. Y.

AIR PUMP.

Application filed May 10, 1923. Serial No. 638,086.

To all whom it may concern:

Be it known that I, JOHN P. QUINN, a citizen of the United States, and a resident of the city of New York, borough of Bronx, 5 in the county of Bronx and State of New York, have invented a new and Improved Air Pump, of which the following is a full, clear, and exact description.

My invention relates to a pump, more particularly an air pump, such as is utilized for the inflation of pneumatic tires for motor vehicles.

It is a well known and appreciated fact in connection with the type of pump specified, that a number of difficulties have been experienced. Thus primarily it has been found, in pumps which have been in use for a certain length of time, that a certain amount of leakage will exist at the point of 20 connection between the cylinder and base thereof.

In this connection it is to be noted further that the construction of the joint at this point has always been more or less of a relatively tedious nature, thus increasing the expense of the finished article, and it is also understood that a further difficulty has been found to exist in that the valve mechanism has not operated properly and the operator 30 has not received the ultimate compression value of the full stroke of the piston.

With these defects in mind, my present invention aims to provide a pump, in which a joint will be formed between the base and 35 the cylinder in such a manner as to virtually preclude any possibility of a leak existing at this point, regardless of the usage to which the pump may be subjected.

A further object of this invention is the 40 construction of a device of the character stated, in which the difficulties incident to the valve mechanism will be eliminated and in which the operator will receive the full compression value of the stroke of the piston.

Still another object of this invention is the provision of a pump which may be placed on the market at a nominal figure, and still further objects will appear in the 50 annexed specification taken in connection with the drawing, which latter presents one practical embodiment of the same and in which—

Figure 1 is a side elevation of a pump embodying my improved construction.

Figure 2 is a transverse sectional side view thereof, and

Figures 3, 4 and 5 are sectional plan views taken along the lines 3—3, 4—4 and 5—5 and in the direction of the arrows indicated in Figure 2.

It will be seen in these views that the reference numeral 10 indicates the cylinder of the pump which may be of any desirable standard construction and within which a 65 plunger 11 extends, a handle 12 being associated with the plunger for the purpose of reciprocating the same. Further, a base 13 of any desired type is provided with which the cylinder 10 is associated in a manner 70 hereinafter described, and a discharge tube 14 is connected with the base, as in the standard types of pumps. Contrary to the conventional construction, however, it will be noted that the plunger 11 is formed with 75 a bore 15 which extends throughout its entire length, an opening 16 being provided adjacent the upper end of this bore through which communication may be had with the outer atmosphere. Further, a piston is af- 80 fixed to the lower end of the plunger 11 and this piston preferably includes a body portion 17, packing elements 18 and clamping nuts 19.

Attention is now invited to Figures 2 and 85 5 and it will be seen in these figures that a valve cage 20 is screwed to the lower end of the plunger 11 and that a check valve 21 co- 90 operates with the valve seat 22 formed at the lower end of the plunger. Also, with a view of avoiding any difficulty incident to back pressure, a relief opening 23 is formed in the upper end of the cylinder 10 and thus it will be understood that upon an operator 95 withdrawing the plunger 11 that the air will be free to flow from within the cylinder 10, through the relief opening 23, the same being also true when the plunger is projected. Further, when the plunger rod is withdrawn, air will flow through the inlet 100

opening 16 and bore 15 of the plunger rod 11, and incident to the fact that the valve 21 is unsealed this air will be free to pass into the compression chamber existent between the piston and the lower end of the cylinder. 105 Immediately upon the direction of the motion of the plunger being reversed, the valve 21 will be seated and the air within the compression chamber will now be compressed and be discharged through the out- 110

let opening 24 in the base 13 and thence into the discharge tubing 14 in return of this air being precluded, incident to the check valve (not shown) associated with the tube 14—
5 this latter feature being conventional construction.

Now, with a view of providing means which will overcome the heretofore existing difficulty at the point of connection of 10 the cylinder with the base, it will be noted that this latter element provides a collar 25 which is internally screw threaded and of a diameter corresponding to that of the cylinder 10. A hollow stud 25' formed with 15 a perforate end 26 is arranged within the collar 25 and it is to be noted that the side walls 27 of the stud taper throughout their entire length, so that a wedge is presented, which wedge preferably presents 20 teeth 28 in its outer face.

The lower end of the cylinder is formed with screw threads corresponding with threads of the collar 25 and these elements may now be associated with each other, and 25 after this has been accomplished a split supplemental collar 29 is introduced into the cylinder 10 and forced to the position shown in Figure 2, it being noted that the side walls of this collar are formed so as to taper 30 to an extent corresponding to the tapering of the side walls of the stud, and further it will be seen that the inner faces of the same are also formed with ratchet teeth corresponding to the ratchet teeth of the member 25'.

In this connection it will, of course, be appreciated that the introduction of the split collar takes place while the plunger rod and piston are removed from the cylinder, and it will thus be seen that upon the collar being forced home that a wedging action will be effected which will serve to pinch the cylinder 10 between the split collar and the collar 25 of the base 13, thus 40 obviously preventing any leakage at this point and providing a connection which will withstand the hardest usage.

It is also to be noted that the supplemental collar 29 may conveniently be formed 50 with projections 30 as in Figure 3, and these projections extend into a grip within corresponding recesses in the cylinder 10, thus preventing any movement of these parts with respect to each other, a movement on

the part of the supplemental collar with 55 respect to the stud being in turn prevented incident to the teeth 28, and finally the stud 25' being retained in position by the cylinder, which is thus providing an interlocking structure.

In the foregoing it will be understood that all the objects set forth in the preamble to this specification are accomplished and it will further be appreciated that numerous improvements of structure might easily be 60 65 allowed without in the least departing from the scope of my claims which are—

1. In a pump, the combination with a base and a cylinder, said base having a screw-threaded recess therein receiving the 70 lower end of the cylinder, a plug centrally located in the cylinder at its lower end, and an expandible ring positioned around the plug and engaging the inner face of the cylinder.

2. In a pump, the combination with a base and a cylinder, said base having a screw-threaded recess therein receiving the lower end of the cylinder, a plug centrally located in the cylinder at its lower end, and an expandible ring positioned around the plug and engaging the inner face of the cylinder, said plug and internal bore of the ring being wedge-shaped in longitudinal section.

3. In a pump, the combination with a base and a cylinder, said base having a screw-threaded recess therein receiving the lower end of the cylinder, a plug centrally located in the cylinder at its lower end, and an expandible ring positioned around the plug and engaging the inner face of the cylinder, said plug and internal bore of the ring being wedge-shaped in longitudinal section, said plug having annular serrations 90 95 engaging the inner face of the ring.

4. In a pump, the combination with a base and a cylinder, said base having a screw-threaded recess therein receiving the lower end of the cylinder, a plug centrally located in the cylinder at its lower end, and an expandible ring positioned around the plug and engaging the inner face of the cylinder, said plug having a base portion 100 105 receiving thereon the lower end of the cylinder.

JOHN P. QUINN.
